Application March 21, 1936, Serial No. 61,723

Term of patent 7 years

To all whom it may concern:

Be it known that I, Samuel M. Wertheimer, a citizen of the United States, residing at Brooklyn, in the county of Kings and State of New York, have invented a new, original, and ornamental Design for a Casing for a Combined Coupling Unit Transformer and Radio Antenna Lead-in Support, of which the following is a specification, reference being had to the accompanying drawing, forming a part thereof.

Figure 1 is a rear face view of the coupling unit of my new design.

Figure 2 is a front face view of my unit.

Figure 3 is a bottom view of the unit.

Figure 4 is an end view.

I claim:

The ornamental design for a casing for a combined coupling unit transformer and radio antenna lead-in support, as shown.

SAMUEL M. WERTHEIMER.
